REFRIGERATOR

Charles D. Bonsall, Pittsburgh, Pa., assignor to
Standard Railway Devices Company, a corpora-
tion of Delaware

Application November 5, 1938, Serial No. 238,970

5 Claims. (Cl. 62—17)

The invention relates to refrigerating cabinets, such as are commonly used in storage houses, railway refrigerator cars, refrigerated trucks and the like, and may be used to refrigerate a railway car or automotive truck. The essential features of such refrigerators are a well insulated cabinet to retard ingress of heat from the surrounding atmosphere and a refrigerating means to keep the inside of the cabinet at a uniformly low temperature. The invention is particularly adaptable to railway refrigerator cars and will be described in reference thereto but is not limited to railway use.

Refrigerator cars are commonly refrigerated by a convective circulation of cooled air, the cooling means being positioned either adjacent the ends of the car or immediately below the roof thereof. The advantages of the latter arrangement are an increased lading space by reason of greater available length and a more effective air circulation due to the increased height of the cooling means. A foraminous floor rack is commonly placed upon the floor of the car and spaced therefrom to allow a space from which the cooled air may filter upwardly through the foraminous rack and cool the lading by contact therewith. Flues associated with the walls of the car communicate with the space under the rack to provide a path for the flow of air from the cooling means to said space and thence to the lading compartment.

The device comprises a system of cooling the air within the cabinet (or car) by a convective or thermo-syphonic circulation of a secondary refrigerating fluid within a closed system, which fluid is cooled by a prime refrigerant.

Any refrigerant may be used, such as water ice, brine, eutectic ice or solid carbon dioxide, commonly called dry ice. Dry ice is particularly suitable because it sublimes to a gas which may be easily disposed of and because its low temperature induces a relatively vigorous circulation of secondary refrigerant.

Any secondary refrigerant may be used which has a low freezing point and wherein the density varies with temperature enough to induce circulation through the conduit.

The object of the invention is to provide a positive and efficient cooling system for a refrigerator in which the temperature may be regulated. Further objects are to conserve lading space of the car and to provide a refrigerating system requiring no power from external sources for operation. Other objects and advantages of the invention will be apparent from the following de-

scription made in reference to the accompanying drawings, in which:

Fig. 1 is a transverse section of a refrigerator car embodying my invention.

5 Figs. 2 and 3 are sections on lines 2—2 and 3—3 respectively of Fig. 1.

Fig. 4 is a view similar to Fig. 1 showing a modified form of my invention.

10 Figs. 5 and 6 are sections on lines 5—5 and 6—6 respectively of Fig. 4.

Fig. 7 is a view similar to Figs. 1 and 4 showing another modified form of my invention.

15 Figs. 8 and 9 are sections on lines 8—8 and 9—9 respectively of Fig. 7.

The parts of the refrigerator car shown in Figs. 1 to 3 are side sill 2; sub-floor 3; floor 4; floor rack 5 spaced above the floor 4 to provide the space 6; side sheathing 7; side lining 8; false wall 9 providing the flue 10; side plate 11; roof

20 12; running board 13; hatch frame 14 surrounding the hatch 15; ceiling 16; partition 17; member 18 and insulation 19. The partition 17 and member 18 cooperate with the ceiling 16 and the upper portion of the side lining 8 to form an enclosing structure 20 for the refrigerant container.

25 The structure 20 has an opening 21 communicating with the flue 10 and an opening 22 communicating with the lading compartment 23. The opening 22 is at a higher elevation than the opening 21 so that the air which is refrigerated and, therefore, densified, will naturally flow through the flue 10.

30 A refrigerant container 30 is positioned within the structure 20. A jacket 31 is in thermally conductive relation with and preferably surrounds the container 30 so that a refrigerant 32

35 in the container, upon melting or subliming, cools a fluid 33 in the jacket. A header 34, which may be designated as the cold fluid header, communicates with the jacket 31 through the pipe

35, said pipe being connected with the jacket adjacent the bottom thereof. Another header 36, which may be designated as the warm fluid header, is disposed substantially parallel with the cold

40 fluid header 34 and preferably at the opposite side of the structure 20 therefrom. A plurality of substantially parallel pipes 37 connect the header 36 with the header 34, some of said pipes

45 37 preferably being disposed between the partition 17 and container 30. The header 36 has communication with the jacket 31 through the pipe 38, said pipe leading to the upper portion of the jacket 31. The pipe 35, header 34, pipes

50 37, header 36 and pipe 38 form a conduit 39 which communicates at both ends thereof with

55

the jacket 31 to form a closed system through which the fluid 33 may circulate. The headers 34-36 may be secured to the car structure by any means, such as the brackets 40-41.

The fluid 33 in the jacket 31, being in thermo-conductive relation with the refrigerant 32, is cooled thereby, while the fluid in the conduit 39 is warmed by air flowing through the structure 20. The fluid in the jacket 31 is, therefore, more dense than that in the conduit so that it flows by convective or thermo-syphonic circulation from the jacket 31 through the pipe 35, header 34, pipes 37, header 36 and pipe 38 to the jacket 31. The heat absorbed by the fluid in the conduit 39 cools and, therefore, densifies the air in the structure 20, causing it to descend through the flue 10 and consequently causing a convective circulation of air, whose path is from the structure 20 downwardly through the flue 10, through the space 6 and upwardly through the lading compartment 23 to the structure 20 through the opening 22.

Insulation 44 preferably is provided around the jacket 31 to retard heat transfer. The circulation of the fluid 33 is dependent upon a relatively large temperature difference between the jacket 31 and the conduit 39. The insulation 44 helps to preserve said difference by preventing the circulating air from warming the fluid in the jacket 31. A thermostatic valve 45 is shown in the pipe 38 to control the temperature of the fluid 33 and, therefore, of the air in the car. It may be preferable to place said valve in the pipe 35.

In the modification shown in Figs. 4 to 6 the conduit 50 comprises a plurality of horizontal pipes 51 disposed within the flue 10. A riser pipe 52 communicates between the lowermost horizontal pipe 53 and the lower portion of the jacket 31. Another riser 54 communicates between the uppermost horizontal pipe 55 and the upper portion of the jacket 31. Connecting portions 56 join alternate ends of the horizontal pipes 51 to form a continuous conduit 50 having both of its ends communicating with the jacket 31. The fluid in the jacket 31, being cooled by the melting or subliming of the refrigerant 32, becomes colder and more dense than the fluid in the conduit 50. The fluid, therefore, circulates convectively or thermo-syphonically from the jacket 31 downwardly through the riser 52 and upwardly through the pipes 51, connecting portions 56 and riser 54 to the upper portion of the jacket 31.

The fluid 33 within the conduit 50 absorbs heat from the air in the flue 10, thereby densifying said air and causing it to descend by gravity. This results in a convective circulation of air downwardly through the flue 10, through the space 6, upwardly through the lading compartment 23, through the opening 22 to the structure 20 and thence to the flue 10.

Figs. 7 to 9 show a modified design in which the parts shown are side sill 2; sub-floor 3; floor 4; floor rack 5 spaced above the floor 4 to provide the space 6; side sheathing 7; side lining 8; false wall 9 providing the flue 10; side plate 11; roof 12; running board 13; hatch frame 14 surrounding the hatch 15; ceiling 16 and insulation 19. A refrigerant container 65 is positioned near the ceiling 16 and spaced from the side lining 8 to allow the space 66 for communication between the lading space 67 and the flue 10. There are also spaces 68 adjacent the container 65 to allow communication between the lading compartment 67 and the flue 10.

A jacket 64 is in thermo-conductive relation

with and preferably surrounds the container 65 so that a refrigerant 32 in the container 65, upon melting or subliming, cools a fluid 69 in the jacket 64. The conduit 70 comprises a plurality of horizontal pipes 71 disposed within the flue 10. A riser pipe 72 communicates between the lowermost horizontal pipe 73 and the lower portion of the jacket 64. Another riser 74 communicates between the uppermost horizontal pipe 75 and the upper portion of the jacket 64. Connecting portions 72 join alternate ends of the horizontal pipes 71 to form a continuous conduit 70 having both of its ends communicating with the jacket 64.

The fluid 69 in the jacket 64, being cooled by the melting or subliming of the refrigerant 32, becomes colder and more dense than the fluid in the conduit 70. The fluid, therefore, circulates convectively or thermo-syphonically from the jacket 64 downwardly through the riser 72 and upwardly through the pipes 71, connecting portions 76 and riser 74 to the upper portion of the jacket 64. The fluid within the conduit 70 absorbs heat from the air in the flue 10, thereby densifying said air and causing it to descend by gravity. This results in a convective circulation of air downwardly through the flue 10, through the space 6 and upwardly through the lading compartment 67 to the top of the flue 10 through the spaces 66-68.

It may be desirable to provide the insulation 80 around the jacket 64 to preserve the temperature difference between the fluid in the jacket 64 and conduit 70 as heretofore explained. The provision of the insulation 80 is also desirable to prevent cooling of the air in the upper portion of the lading compartment 67. Cool air in said upper portion would settle downwardly through the lading compartment 70, thus interfering with the intended circulation which is upwardly. The insulation 81-82 on the risers 72-74 may also be provided to prevent the above mentioned settling of air in the lading compartment.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In combination with the walls, roof and floor of a refrigerator car, a foraminous rack arranged to support a lading upon said floor and provide a space therebetween, a flue associated with one of said walls and communicating at its lower end with said space, a refrigerant container below said roof, a substantially horizontal partition spaced below said container to provide a duct therebetween arranged to conduct air from said lading compartment to the upper part of said flue, a header disposed substantially parallel with said last mentioned wall on each side of said container, a plurality of spaced apart conduits disposed in said duct substantially parallel with the direction of air flow therethrough, said conduits communicating between said headers, means to utilize a refrigerant in said container to cool a fluid, and means arranged so that said refrigerant induces a circulation of said cooled fluid from one of said headers through said conduits to the other of said headers.

2. In combination with the walls, roof and floor of a refrigerator car, a foraminous rack arranged

to support a lading upon said floor and provide a space therebetween, a flue associated with one of said walls and communicating at its lower end with said space, a refrigerant container below said roof, a substantially horizontal partition spaced below said container to provide a duct therebetween arranged to conduct air from said lading compartment to the upper part of said flue, a jacket in thermo-conductive relation with said container, a header disposed substantially parallel with said last mentioned wall on each side of said container, a plurality of conduits disposed in said duct substantially parallel with the direction of air flow therethrough, said conduits communicating between said headers, and means to provide communication between said headers and said jacket, one at a higher level than the other.

3. In combination with the walls, roof and floor of a refrigerator car, a foraminous rack arranged to support a lading upon said floor and provide a space therebetween, a flue associated with one of said walls and communicating at its lower end with said space, a refrigerant container below said roof, a substantially horizontal partition spaced below said container to provide a duct therebetween arranged to conduct air from said lading compartment to the upper part of said flue, a jacket in thermo-conductive relation with said container, a header disposed substantially parallel with said last mentioned wall on each side of said container in spaced relation above said partition, a plurality of substantially parallel conduits disposed in said duct transverse to said last mentioned wall and communicating between said headers, said conduits having upturned ends which communicate with said headers, means to provide communication between one of said headers and said jacket, and means at a higher level than the first mentioned means

5 to provide communication between the other of said headers and said jacket.

4. In a refrigerator car having walls, roof and floor which define a lading compartment, a foraminous rack arranged to support a lading upon said floor and provide a space therebetween, a flue associated with one of said walls and communicating at its lower end with said space, a refrigerant container below said roof in spaced relation to said last mentioned wall to form a chamber therebetween having communication with said lading compartment and with the upper part of said flue, a conduit having a part thereof disposed within said flue and another part thereof extending through said chamber, means to insulate the part of said conduit within said chamber, means to utilize a refrigerant in said container to cool a flue, and means arranged so that said refrigerant induces a circulation of said cooled fluid through said conduit.

5. In a refrigerator car having walls, roof and floor which define a lading compartment, a foraminous rack arranged to support a lading upon said floor and provide a space therebetween, a flue associated with one of said walls and communicating at its lower end with said space, a refrigerant container below said roof in spaced relation to said last mentioned wall to form a chamber therebetween having communication with said lading compartment and with the upper part of said flue, a jacket in thermo-conductive relation with said container, a conduit having the middle part thereof disposed within said flue and the end parts thereof extending through said chamber and communicating with said jacket, one end at a higher level than the other end, and means to insulate the part of said conduit within said chamber.

CHARLES D. BONSALL.
